Patented Nov. 22, 1921.

Samuel M. Kathcart.

By Watson E. Clemen
Attorney

UNITED STATES PATENT OFFICE.

SAMUEL M. KATHCART, OF LEADWOOD, MISSOURI, ASSIGNOR OF ONE-HALF TO
WILLIAM H. COOPER, OF LEADWOOD, MISSOURI.

WRENCH.

1,397,638.

Specification of Letters Patent.

Patented Nov. 22, 1921.

Application filed October 21, 1920. Serial No. 418,383.

To all whom it may concern:

Be it known that SAMUEL M. KATHCART, a citizen of the United States, residing at Leadwood, in the county of St. Francois and 5 State of Missouri, has invented certain new and useful Improvements in Wrenches, of which the following is a specification, reference being had to the accompanying drawings.

10 This invention relates to wrenches and particularly to a quick adjustable wrench.

An object of the invention is to provide a wrench of this character including a stationary and a movable jaw member, one end 15 of the movable jaw member providing a jaw so as to thereby eliminate projections and strengthen the wrench.

Another object is to provide a wrench of this character including a stationary and 20 movable jaw member, the stationary jaw having a housing in which the movable jaw member is slidably mounted, the housing and jaw of the stationary member limiting movement of the movable jaw member.

25 Another object of the invention is to provide a wrench of this character including a stationary shank having a jaw on one end and a housing on the opposite end in alinement with the jaw, and a movable jaw 30 slideable in the housing and having an enlargement disposed in alinement with the housing and the stationary jaw, said movable jaw being capable of disengagement from the housing when extended obliquely thereof 35 by the removal of the locking means of the wrench.

With the above and other objects in view, the invention consists in the improved construction and arrangement of parts to be 40 hereinafter more particularly described, fully claimed and illustrated in the accompanying drawings, in which:—

Figure 1 is a side elevation of a wrench constructed in accordance with an embodiment of the invention,

Fig. 2 is a side elevation showing the manner of disassembling the wrench, the locking lever and guide being removed,

Fig. 3 is a side elevation and sectional view of the stationary shank and jaw showing the interior of the housing, and

Fig. 4 is a rear elevation.

Referring to the drawings, 5 designates a stationary shank having a stationary jaw 6 projecting from one end in right angular

relation to the shank, one surface of the jaw being provided with teeth 7. The opposite end of the shank is bifurcated to provide arms 8, the end of said bifurcated end being provided with divergent canted surfaces 9 and 9^a. These canted portions permit the parts of the wrench to be separated. Formed integral with the bifurcated portion 8, is a housing 10, the sides of the housing merging with the arms 8. In view 65 of this, the housing is open at its side 11 through the medium of the bifurcated portion and at its ends 12. Formed in each of the sides 13 of the housing is an elongated slot 14, which register with each other. In view 70 of this novel construction, the only portion which connects the sides of the housing and the arms 8, is the side 15 of the housing and the canted portions 9 and 9^a. 75

A movable shank 16 is slidably disposed within the housing 10 and is movable through the ends 12 thereof. The end portion 17 of the movable jaw includes an enlargement 18 providing a stop shoulder 19 80 adapted to engage the inner end 12 of the housing to limit movement of the movable shank in one direction. The end of the enlargement or shank is provided with teeth 20 and serves as a movable jaw. By this 85 novel construction, the jaw does not project from the side of the shank 16 but is formed on one end of the shank so that it is disposed at all times in alinement with the jaw 6 and the housing 10, the jaw 6 90 limiting movement of the shank in one direction. The enlargement 18, lies flush with the side 21 of the shank so as to permit the shank to slide freely on the stationary shank 5. The side 21 is provided with a 95 plurality of teeth 22 and a stop member 23.

A locking lever 24 is employed to lock the movable shank 16 in its adjusted positions. This lever is provided with an enlargement 25, and has its end 26 canted. 100 A plurality of teeth 27 are formed in one side of the enlargement 25, while an opening 28 is formed adjacent the canted end 26 and is adapted to receive a detachable pivot pin 28 which is also disposed in the slots 14. 105 The teeth 27 of the lever are arranged for interlocking engagement with the teeth 22 of the movable shank to hold the shank in its locked position. An important feature of the slots 14 is that they permit the wrench 110

to be adjusted after the jaws are engaged with an object. This would not be possible if pivot openings instead of the slots were employed as the canted end of the lever would contact with the teeth 27, and prevent the lever from being positioned parallel to the movable shank 16. The slots 14 permit the lever 24 to move freely in the adjustment of the wrench. To properly position the enlargement 18 on the shank 5, a U-shaped guide member 29 is provided, and has its ends detachably pivoted to the enlargement 18, and is adapted to embrace the shank 5 to guide the movable shank and bear a portion of the burden which would ordinarily be transmitted to the pivot pin 28 and the housing 10.

In the adjustment of the wrench, as previously stated, the jaws may be applied to the object and the lever then adjusted in view of the slots 14, or the jaws may be adjusted before being applied to the work. This is accomplished by moving the lever 24 away from the shank 16 and sliding the shank to the desired position. The lever is then moved toward and into parallel relation with the shank 16 so as to permit the teeth 22 and 27 to interlock, thereby lock the wrench in its adjusted position. In view of the fact that the jaw of the shank 16 is disposed at all times in alinement with the housing 10 and jaw 6 it is impossible to disengage the jaw from the wrench as long as it is in this position. However, if repairs are necessary the movable shank 16 can be readily disengaged from the stationary shank, by removing the guide member

29, and the pivot pin 28. This permits the lever 24 to be disengaged from the housing 10, whereupon the shank 16 may be disposed 40 obliquely of the shank 5 in view of the canted portions and readily removed from the housing 10.

From the foregoing it will be readily seen that this invention provides a novel form 45 of wrench capable of being adjusted quickly and accurately. It is impossible for the movable jaw to slip from its adjusted position, as the shank 5 and housing 10 do not form part of the handle, the handle being 50 formed by the co-operation of the end of the shank 16 with the lever 24. In addition to these features, it is composed of a few simple parts which can be readily assembled and disassembled.

What I claim is:—

A wrench comprising a stationary shank, a jaw projecting from one side of the shank, a housing formed on the opposite end of the shank in alinement with the jaw, the ends 60 and one side of said housing being open, a movable handle having an enlarged end portion, the extremity of said end portion forming a jaw, said handle being slidable through the housing, one end of the housing limiting movement of the handle in one direction, a guide member pivoted to said enlarged end portion and embracing the stationary shank, and a locking lever pivoted in the open side of the housing and arranged 65 for interlocking engagement with the handle.

In testimony whereof I hereunto affix my signature.

SAMUEL M. KATHCART.
